UNITED STATES PATENT OFFICE.

DAVID REIS BOWEN, OF ANSONIA, CONNECTICUT, ASSIGNOR TO FARREL FOUNDRY & MACHINE COMPANY, OF ANSONIA, CONNECTICUT.

CALENDER OR THE LIKE.

Application filed October 25, 1920. Serial No. 419,217.

To all whom it may concern:

Be it known that I, DAVID R. BOWEN, a citizen of the United States, residing in the town of Ansonia, county of New Haven, and State of Connecticut, have invented certain new and useful Improvements in Calenders or the like, of which the following is a full, true, and exact description.

This invention relates to calenders and particularly to the supporting structure for the rolls.

In the types of calendering machines now in general use, a series of rolls are mounted in superposed relation in vertical standards or housings to form what is ordinarily termed a "stack." These vertical housings usually form the sole supports for the rolls and other parts of the calenders, which, being large and heavy machines necessarily should have strong and rigid supporting members of relatively large base area. It is particularly important that these machines should be rigidly supported when used in connection with the fine gauging of soft rubber and the like. My improvements are designed to increase the rigidity of the supporting structure.

It is also common in the calender machines now in use for the ends of rolls or roll "necks" and the gears secured thereon to project beyond the standards or housings where they are in an exposed position and the clothing of the operator is apt to come into contact with the roll necks or to get caught in the gears. My improvements are also designed to overcome this defect, present in the machines heretofore used.

One object of this invention is to provide a calender of generally improved construction and operation.

Another object of this invention is to materially increase the rigidity of the vertical standards or housings in machines of this character.

A further object of the invention is to provide the vertical standards with means to enclose the roll ends and gears thereon, so that they will not be in an exposed position in operation.

To these and other ends the invention resides in the novel features and combinations of parts to be hereinafter described and claimed.

In the accompanying drawings:

Fig. 1 is a front elevational view of a

calender machine embodying the improvements of my invention.

Fig. 2 is an end view of the same.

Fig. 3 is an enlarged front elevation of one of my improved supporting standards.

Fig. 4 is an end view of the structure shown in Fig. 3.

Fig. 5 is a sectional plan view on line 5—5 of Fig. 4 looking in the direction of the arrows.

The embodiment of my invention which I have chosen to illustrate in the drawings accompanying this application comprises a stack of calender rolls 11, supported in two vertical standards 12, which are spanned at the top by a supporting table 13. These rolls may be supported in the standards 12 in any suitable manner. As shown in the drawings, each of the standards 12, consists of two substantially parallel spaced members 12^a which are joined at their lower ends by the base web 12^b, thus providing longitudinal openings 14 in which are suitably secured journal boxes 15 which rotatably receive the spindles or roll necks 16 of the rolls 11.

I have illustrated my invention as applied to a calender having an overhead motor drive of a type known prior to my invention and to which I make no claim. The drive mechanism for the rolls is supported upon the upper ends of the standards 12 and the table 13. This drive mechanism consists of a suitable electric motor or source of power 17, which is operatively connected with a shaft 18 journaled upon the supporting table 13 and carrying a pinion 19 on one end, which meshes with a gear 20, which is secured to one end of the middle roll spindle 16. The pinion 19 and the gear 20 are suitably enclosed in a housing 21.

It will be seen by reference to the drawings that the roll necks or spindles 16 project beyond the body portions of the standards 12 and the gears 22 which are secured to the left ends of the spindles 16 are not protected by such body portions. Moreover, it will also be apparent that the supporting table 13 and the upper ends of the standard 12 will be required to support a weight of great magnitude in the structure of the calender rolls themselves and of the driving mechanism which is, in the embodiment shown, located on the top of the machine frame. It is, therefore, important to provide standards of great rigidity which

will be able to bear the required weight, and which will be able to provide a rigid support for the device notwithstanding the vibrations of the machine when in operation. 6 This will be found particularly desirable when the machine is used on the fine gauging of soft rubber.

The vertical standards 12 are, therefore, provided with flanges 23, one of which extends laterally from the panels on each side of the longitudinal openings 14. As shown, in Figs. 3, 4 and 5, these flanges extend vertically throughout the entire length of the standards 12 and the upper portions thereof 15 assist in supporting the broadened upper surfaces 24 which connect the upper ends of members 19^a and cooperate with the supporting table 13 in providing a base for the drive mechanism. It will be apparent that 20 these flanges not only give rigidity to the standards 12, but by their continuation to the upper ends of these standards they serve as a firm underpinning for the supporting surfaces 24.

25 The upper bases 24 are provided at their inner faces with shoulders 24^a which cooperate with complementary shoulders 13^a formed on the end surfaces of the table 13. This provides a rigid support for the table 30 and at the same time furnishes a flat supporting base for the driving mechanism as the upper surfaces of the member 24 and table 13 are in the same plane. Bolts 27 are then passed through aligning openings in 35 the standards and table to secure the parts firmly together.

As shown in Figs. 1, 3 and 5 of the drawing, these flanges extend laterally from the standards 12, and in the general longitudinal 40 direction of the rolls 11 to a sufficient distance to form housings for the roll necks or spindles 16, which, as has been stated, project beyond the body portion of the standards 12. The gears 22 which are provided 45 on one of the ends of the rolls 11 will also lie within the space between these flanges, which therefore serve as a housing for these gears. The spindle ends on the right side of the machine, as shown in Fig. 1, will project 50 into the space between the flanges, so that the flanges will serve as a housing to protect the otherwise exposed ends of the spindles. The flange portions may, as shown, be cast in one piece with the standards 12, or if desired, they may be separately 55 provided and secured to the standards by bolting or other suitable means. The flanges 23, as well as the standards 12, will be provided with base portions 25 through which 60 suitable pins or bolts 26 may be inserted to secure the machine in position upon a suitable base. The continuation of the flanges to the lower ends of the standard and the provision of the broadened base portions on the same will greatly increase the base area

of the standards and thereby increase their stability and that of the device as a whole. The calender will, therefore, be supported rigidly and will be less subject to vibrations in operation. Furthermore, the outwardly 70 extending flanges, which are of such depth as to form housings or protecting members for the outer ends of the roll necks and the gears mounted on certain of said roll necks, are an important safety factor in the operation of the machine in so far as the protected parts, in the normal operation of the machine, are not likely to catch the persons or the clothing of the attendants, as has been the case hitherto in machines with exposed 75 roll ends; and again these flanges have an important function in supporting from beneath a drive mechanism of greater base length than the distance between the outer faces of the body portions of the standards 80 or end frames.

It will be apparent that it is particularly advantageous to use my improved construction of the supporting standards and the frame of the machine in combination with 85 an overhead drive of the type shown. The electric motor and other parts of the drive mechanism supported upon the upper ends of the standards and the table 13 are of great weight and will require a strong and rigid standard construction. The center of gravity of the whole device is raised by the positioning of the driving members upon the top of the roll stack so that a broader base area is needed to provide a stable support as well as a stronger direct supporting 90 means to carry the weight of the motor and associated driving elements. Moreover, the vibrations of the motor when in operation will be transmitted to the frame and to overcome this effect it is also particularly desirable to use my novel standard construction wherein the vibrations of the calender are 95 reduced to a minimum. It will be understood, however, from what has been said above that I make no claim to the overhead drive per se, but only in combination with the improved frame construction of my invention.

100 While I have illustrated in the drawings and described a preferred embodiment of my invention, it will be understood that I do not intend to be limited in all of its details to the exact form shown and described, for the invention is capable of many modifications and of various changes which will lie within the scope of the appended claims.

105 What I claim is:

110 1. A calender comprising spaced standards, a roll stack supported thereby, said rolls having spindles journaled in said standards, the ends of the spindles projecting through one of the standards and being 115 provided with gears, and flanges, on said standard, forming a housing for said gears. 120

2. A calendering machine comprising a roll stack, supporting standards therefor, the rolls of said stack being provided with spindles rotatably supported by said standards with the spindle ends projecting through one of said standards and provided with gears on these projecting ends, and means on said standard to strengthen the same and form a housing for said gears.
- 10 3. A calendering machine comprising a roll stack, supporting standards therefor, the rolls of said stack being provided with spindles rotatably supported by said standards with the spindle ends projecting through one of said standards and provided with gears on these projecting ends, and a pair of opposing flanges on said standard, coextensive in length therewith, to increase the rigidity thereof and form a housing for 20 said gears.
4. A supporting standard for calenders or the like, having a base and an upper broadened portion projecting laterally beyond the body portion thereof, such broadened portion being of such extent as to form a substantial part of a motor drive platform, and a gear-housing flange projecting laterally from the body portion of the standard and extending from the base thereof 30 to said upper broadened portion and integrally joined to said broadened portion.
5. A supporting standard for calenders or the like, having upper and lower broadened surfaces projecting laterally beyond the body portion thereof, the upper of such surfaces being of such extent as to form a substantial part of a motor drive platform, and gear-housing flanges projecting laterally from the body portion of the standard 35 and extending across the space between the upper and lower broadened surfaces thereof, said flanges being of a depth substantially equal to the projection of the upper and lower broadened surfaces laterally beyond 40 the standard.
6. A calender or the like, having a roll stack, end standards supporting the same, a table spanning the standards above the rolls, said standards having broadened upper ends cooperating with the table to provide a motor drive platform projecting laterally beyond the bodies of the respective standards, a motor drive mounted on said platform, and gear housing flanges extending substantially throughout the length of 55 the standards and located below the later-
- ally projecting portions of the motor drive platform to support the same from beneath.
7. A calender or the like, including a roll stack, end frames for supporting the same, an overhead motor drive mechanism on top of the end frames and of greater base length than the distance between the outer portions of the bodies of said end frames, said platform including laterally projecting members associated with the upper ends of the respective standards, and gear-housing flanges running along the standards on the outer sides thereof and of a depth substantially corresponding to the overhang of said laterally projecting members.
8. A calender or the like, including a roll stack, end frames supporting the same, an overhead motor drive on top of the end frames, a motor drive platform including a table portion spanning the end frames and also including members at the upper ends of the end frames extending outward therefrom in a lateral direction, a flange extending lengthwise along one of said end frames and of a depth substantially equal to the overhang of the motor drive platform, and a gear on the end of at least one of the roll shafts housed and protected by said flange.
9. A calendering machine having end frames, rolls journaled therein, gearing associated with said rolls, an overhead motor drive mechanism, a platform for supporting said motor drive mechanism, associated with the upper ends of said frames, and a common means for housing a considerable portion of the gearing and for supporting from beneath a substantial portion of the motor drive platform.
10. A calendering machine having end frames, rolls journaled therein, gearing associated with said rolls, an overhead motor drive mechanism, a platform for supporting said motor drive mechanism, associated with the upper ends of said frames, and a common means for enclosing a considerable portion of the gearing and for supporting from beneath a substantial portion of the motor drive platform, said means including a relatively deep flange running lengthwise along one of said frames substantially from the bottom to the top thereof at the outer face of the same.
- In witness whereof, I have hereunto set my hand this 18th day of October, 1920.
- DAVID REIS BOWEN.
